UNITED STATES PATENT OFFICE

LEO MARDER, OF BROOKLYN, NEW YORK

DESIGN FOR A HAND MIRROR

Application filed May 4, 1933. Serial No. 48,006. Term of patent 7 years.

To all whom it may concern:

Be it known that I, LEO MARDER, a citizen of the United States, residing at Brooklyn, in the county of Kings and State of New York, have invented a new, original, and ornamental Design for Hand Mirrors, of which the following is a specification, reference being had to the accompanying drawing, forming part thereof.

In the accompanying drawing:

Fig. 1 is a plan view of the mirror made in accordance with my design; and

Fig. 2 is a side view of the mirror shown in Fig. 1.

I claim:

The ornamental design for a hand mirror, as shown.

In testimony whereof, I have hereunto subscribed my name.

LEO MARDER.
